UNITED STATES PATENT OFFICE.

MICHEAL P. PREGLER, OF CHICAGO, ILLINOIS.

SCRUBBING-MACHINE.

1,329,474.

Specification of Letters Patent. Patented Feb. 3, 1920.

Application filed February 20, 1918. Serial No. 218,257.

To all whom it may concern:

Be it known that I, MICHEAL P. PREGLER, a citizen of the United States, residing at Chicago, in the county of Cook and State 5 of Illinois, have invented certain new and useful Improvements in Scrubbing-Machines, of which the following is a specification.

This invention relates to scrubbers, and 10 more especially it is a scrubbing machine wherein the brush is rotated on its own upright axis as it is drawn along the surface being scrubbed, and wherein water is applied to and through the brush to said surface. While I have described and illustrated the device as employed for the purpose of scrubbing, it is quite obvious that 15 it could be used for other purposes such as sweeping, dry-cleaning, and perhaps waxing floors, or cleaning the same with other liquids than water, and I reserve the widest latitude in the uses to which this machine 20 may be put.

Details of construction will be found in 25 the following specification, and reference is made to the accompanying drawings, wherein:—

Figure 1 is a side elevation of this apparatus complete,

Fig. 2 is an enlarged detail of the connection between the main shaft or axle and the center of the scrubber,

Fig. 3 is a rear elevation on a larger scale than Fig. 1 with the scrubber in vertical 35 section,

Fig. 4 is a plan view of the scrubber.

Wheels 1 are mounted rigidly on a main shaft or axle 2 journaled in bearings 3 in a frame 4 from which a yoke 5 leads forward to a handle 6, the yoke being preferably supported or braced as at 7 as seen in Fig. 1. A tank or reservoir 8 is carried on the frame and has an outlet 9 controlled by a hand valve as shown. A driving bevel 40 gear 10 is mounted fast on the axle near the center of the frame. From a plate 11 secured beneath the center of the frame depends an upright hanger 12 preferably having a bearing 13 for the axle 2, and its lower 45 end is threaded as at 14 to receive a nut 15 and a washer 16. Above said washer there is loosely mounted on the hanger a pair of plates 17 and 18, the uppermost having a collar 19 carrying a bevel gear 20 which meshes 50 with the driving gear 10, and ball bearings 55 21 may be employed to reduce friction as

this structure rotates around the lower end of the hanger which therefore becomes its support. Between said plates 17 and 18 are clamped the inner ends of radiating arms 60 22, preferably four in number and of channeled cross section as shown, and the outer ends of these arms are united by an upright annular band or ring 23 of sheet metal whose lower edge rests on the ground 65 or floor or stands very near the same, and whose purpose is to prevent splashing. This band or ring may be removed if desired, but I prefer to employ it. Thus is built up a spider structure which supports the 70 brush proper, the elements illustrated in Fig. 2 constituting the hub of this spider rotatably mounted around the lower end of the hanger 12, and the entire spider is driven by the intermeshing of the gear 20 75 with the power or driving gear 10 on the main axle 2. Therefore as the machine is drawn forward by its handle, the rotation of the axle automatically causes the rotation of the spider.

The scrubbing brush is by preference made in separate elements. Each has a back-piece 25 fitted adjustably into the channel of one of the arms 22, and bristles 26 depending from said piece. The latter carries on its upper side at two or more points socket plates 27 within which are swiveled heads at the lower end of screws 28 which are threaded through the top of the arm containing the back piece referred to. By 80 setting up the screws the brush may be raised, and by loosening the screws the brush may be lowered so that its bristles make a closer contact with the floor or surface being scrubbed.

When in use, water is permitted to flow by setting the valve within the outlet 9, and as the machine progresses forward and the entire scrubber rotates, the water passes through the rotating spider between the 100 arms thereof and falls onto the surface being scrubbed. Here it is carried around by the bristles of the various brushes, and the band or ring 23 prevents splashing contiguous objects. If other liquid than water is desired, it may of course be employed. One only of the main wheels 1 may be loose on the axle 2 so as to permit the machine to be turned; but this detail is well known in many arts and I have not illustrated it. Also, for 105 domestic use said wheels would probably have rubber tires so that they would not in-

jure the finest floor or any furniture with which they come in contact. Otherwise the materials and proportions of parts may well be left to the manufacturer.

5 What is claimed as new is:—

In a scrubbing machine, the combination with a tank having a valved outlet pipe in its bottom, a main axle and wheels, an inverted U-shaped frame supporting the tank, 10 and having bearings in which said axle is journaled, means for attaching said tank to said frame, a disk secured to said frame

intermediate its ends, an upright hanger integrally depending from said disk and provided with a bearing for said axle, the end 15 of said hanger provided with means for rotatably carrying a brush, and means provided for rotating said brush.

In testimony whereof I affix my signature in presence of two witnesses.

MICHEAL P. PREGLER.
